REFRIGERATING APPARATUS

Andrew C. Freimann, Dayton, Ohio, assignor to
 General Motors Corporation, Dayton, Ohio, a
 corporation of Delaware

Application December 30, 1941, Serial No. 424,950

10 Claims. (Cl. 62—6)

This invention relates to refrigerating apparatus and more particularly to an improved refrigerating system for use in conditioning the air for private homes or the like.

Notwithstanding the fact that the residential air conditioning field represents one of the largest potential markets for air conditioning apparatus, the residential air conditioning field remains substantially untouched. The problems involved in designing low cost residential air conditioning apparatus suitable for use in all types and sizes of homes, in all climates, explains to a large extent why the prior art type of residential air conditioning systems have not gone into more extensive use.

It is an object of this invention to provide low cost air conditioning apparatus adaptable to mass production and capable of universal application in air conditioning private homes and the like.

More particularly, it is an object of this invention to provide a ductless air conditioning system capable of efficiently conditioning 100% fresh air throughout widely varying air conditioning loads.

A further object of this invention is to provide improved control means for use in air conditioning systems in which the air to be conditioned flows in thermal exchange with two separate evaporators.

Another object of this invention is to provide a system capable of efficiently conditioning all fresh air and having means for effectively varying the air conditioning capacity throughout a wide range of inside and outside air temperatures.

Still another object of this invention is to provide an improved control for varying the ratio of sensible cooling to latent cooling.

A further object of this invention is to provide an improved means for starting and stopping the operation of a plurality of refrigerant liquefying units serving a common air conditioning load.

Further objects and advantages of the present invention will be apparent from the following description, reference being had to the accompanying drawings, wherein a preferred form of the present invention is clearly shown.

In the drawings:

Fig. 1 is a vertical sectional view diagrammatically showing an air conditioning system constructed in accordance with my invention installed in a private home;

Fig. 2 is a vertical sectional view of the apparatus showing the arrangement of the elements;

Fig. 3 is a vertical sectional view showing two self-contained air conditioning units of similar construction connected in tandem;

Fig. 4 is a diagrammatic view showing the various controls used.

For purposes of illustration, I have shown my system applied to a conventional two-story dwelling 10 having an attic space 12 in which the entire conditioning system is mounted. The air conditioning apparatus comprises two self-contained air conditioning units 14 and 16 through which the air to be conditioned is adapted to pass in series. Air to be conditioned enters the attic space through a suitable opening, such as an attic window 18. The air enters the first unit 14 through the air inlet 20 and discharges downwardly from the second unit 16 into the second floor hallway 22 from whence a portion of the conditioned air discharges into the second floor bedrooms 24 and another portion of the air discharges downwardly through the stairway 26. The air coming down through the stairway 26 is distributed to the first floor rooms 28 through the various doorways and openings leading from the stairway 26. Inasmuch as all of the air which is conditioned is taken from the outside through the attic window 18, it is apparent that a corresponding amount of vitiated air must be discharged to the outside from the conditioned space. In order to allow air to discharge from the conditioned rooms, some or all of the windows are permitted to remain open. Under normal conditions, the amount of conditioned air discharged into any one room will be determined in part by the amount that the windows in that room are open, and in part by the size of the air passageway between the hallway and that room. If necessary, booster or exhaust fans may be added to facilitate air distribution within the house.

Referring now to Fig. 3 in which I have shown a vertical sectional view of the units 14 and 16, it will be observed that the air to be conditioned enters the unit 14 through the inlet 20 adjacent which is provided a filter 30. The incoming air first flows in thermal exchange relationship with a water coil 32 and thereafter flows in thermal exchange relationship with a volatile refrigerant evaporator 34, both of which are arranged in the unit 14. The volatile refrigerant evaporator 34 is supplied with liquid refrigerant by the motor-compressor-condenser unit 36. The flow of refrigerant to the evaporator is controlled by a conventional pressure reducing element 37 which may be either an automatic expansion

valve or a fixed restrictor. For a complete description of the construction of the unit 36, reference is hereby made to application 326,883 filed March 30, 1940. A blower unit 38 driven by a motor 39 is mounted in the bottom portion of the unit 14 and is adapted to discharge the air flowing over the coils 32 and 34, into a plenum chamber 40 which is removably secured to the unit 14.

When maximum refrigeration capacity is required, the conditioned air flows from the plenum chamber 40 through the damper 42 into the upper compartment 44 of the self-contained unit 16, as shown by the solid line arrows in Fig. 3. A volatile refrigerant evaporator 46 is mounted in the compartment 44 and is adapted to further cool the air whenever the damper 42 is open or partially open. Refrigerant is supplied to the evaporator 46 by means of a motor-compressor-condenser unit 47 which is similar to the unit 36. The air leaving the evaporator 46 flows downwardly into the lower compartment 48 of the second unit 16 where it is picked up by the blower 50 and is discharged into the plenum chamber 52. The blower 50 is driven by the motor 51 located in the compartment 48. The plenum chamber 52 is provided with an opening 54 in the bottom wall thereof through which the conditioned air is discharged downwardly into the space below, as best shown in Fig. 1. An air distributing plaque 56 may be provided adjacent the conditioned air outlet so as to distribute the air horizontally along the ceiling of the hallway.

Since the amount of refrigeration required varies from time to time, it is apparent that some means must be provided for varying the amount of cooling which takes place. As shown in Fig. 3, the unit 16 is provided with a damper 58 which when open allows a portion or all of the air to bypass the evaporator 46, as shown by the dotted line arrows in Fig. 3. The dampers 42 and 58 are both operated by means of a single damper motor 59 which will be described more fully hereinafter. The arrangement of the damper operating mechanism is such that the damper 42 moves towards "closed" position when the damper 58 is moved toward "open" position. By virtue of this arrangement, it is possible to vary the amount of sensible cooling by varying the amount of air flowing in thermal exchange with the evaporator 46.

In order to more clearly illustrate the operation of the system and the controls for the system, I have included a diagrammatic showing of the apparatus in Fig. 4. Referring now to Fig. 4, it will be observed that the dampers 42 and 58 are both operated by means of the reciprocating bar 60 which operates the dampers 42 and 58 through the pin and slot connections 61 and 63 respectively. The upper end of the bar 60 is pivotally connected to a lever 62 which merely serves to guide the upper end of the bar 60. The lower end of the bar 60 is pivotally connected to a similar lever 64. Movement is imparted to the bar through the lever 66 which in turn is actuated by the lever 68. Lever 68 is pivotally supported on the stationary element 70. For purposes of illustration, I have shown the lever 68 operated by means of a bellows 72. The bellows 72 is connected to a thermostatic bulb 74 charged with a fluid which expands and contracts upon increases and decreases respectively in the air temperature. The thermostatic bulb 74 is preferably mounted in the conditioned space. The refrigerant liquefying unit 47 which supplies

liquid refrigerant to the evaporator 46 is controlled by means of a switch 76, which in turn is controlled by the bulb 74 through the lever 68 and the switch operating arm 78 carried thereby. The arrangement of the arm 78 and the switch 76 is such that the arm 78 does not open the switch 76 until the damper 42 has been moved to a position in which all or substantially all of the air by-passes the evaporator 46. A back pressure regulating valve 79 of conventional construction is provided in the suction line leading from the evaporator 46 to the unit 47 and serves to limit the suction on the evaporator so as to prevent the evaporator from becoming cold enough to freeze the condensate when some of the air is by-passed.

Reference numeral 80 designates the main power supply lines. A manually operated switch 82 is provided in the main power supply line, as shown, and serves as a master control switch for shutting down the entire air conditioning system. An automatically controlled switch 84 is also provided for starting and stopping the operation of the entire system. The switch 84 is controlled in response to the incoming air temperature by means of the thermostat 86 and the bellows 88. While I have shown the thermostat 86 mounted in the incoming air stream so as to be responsive to the outside air temperature, it is apparent that this thermostat could be located so as to respond to the temperature of the air leaving the air conditioning apparatus, or so as to respond to the air in the conditioned space.

The blower motors 39 and 51 are arranged in series with the switch 84, as shown. Electrical energy is supplied to the motor-compressor units 36 and 47 through the lines 80 and 82. A switch 94 is placed in the circuit leading to the motor-compressor-condenser unit 36. The switch 94 is controlled by the thermostat 86 which is preferably located so as to respond to the temperature within the conditioned space. The thermostat 86 controls the switch 94 through the medium of the bellows 88. The thermostat 86 is so calibrated as to open the switch 94 at a lower temperature than the temperature at which the switch 76 is adapted to be opened by the thermostat 74. By virtue of this arrangement, the first self-contained unit 14 will be the only unit to operate when the air conditioning load is light. The second self-contained unit 16 will not come into operation until the demand for cooling increases beyond the point at which the unit 14 is capable of supplying the necessary amount of cooling.

The incoming fresh air will deposit moisture on the water coil 32 and the evaporator 34 under most climatic conditions. This condensate will be discharged to a drain through the condensate drain line 100. A considerable amount of moisture will also be removed from the air by the evaporator 46. Drain line 101 has been provided for draining away the condensate removed from the air by the evaporator 46.

As best shown in Fig. 4, water from any suitable source such as the city main is supplied through the line 102. Water from the line 102 flows into the water coil 32 through the line 103. Water leaving the coil 32 flows through the line 104 to the water inlet of the motor-compressor-condenser unit 36 and is used for condensing the refrigerant within the unit 36. The water thereafter leaves the unit 36 through the line 105 which connects to the main drain line 106. The flow of water through the water coil 32 and

through the condenser cooling portion of the motor-compressor-condenser unit 36 is controlled by the valve 107 which in turn is controlled by the condensing pressure. The valve 107 is of conventional construction and is adapted to increase the flow of water as the condensing pressure increases and to decrease the flow of water as the condensing pressure decreases. A small line 108 provides communication between the interior of the condensing chamber and the valve 107.

In most communities, the prevailing water temperatures are low enough so that the incoming water is capable of removing an appreciable quantity of heat from the relatively hot outside air. Inasmuch as the condensing temperature of the refrigerating system is considerably higher than the temperature of the air leaving the water coil 32, it is obvious that the water leaving the coil 32 is still effective for condenser cooling purposes.

When the motor-compressor-condenser unit 47 is in operation, condenser cooling water is supplied thereto through the line 109 and returns to the drain through the line 110. The flow of water to the unit 47 is controlled by the valve 111 which is similar in construction and operation to the valve 107 described hereinabove. The line 112 provides communication between the interior of the condensing chamber and the valve 111.

In small homes when the air conditioning load does not warrant the use of two self-contained units, as shown in this application, only one unit would be used. Thus, in a small home, either one or the other of the units 14 or 16 would be omitted. By virtue of this fact, it is obvious that only one size motor-compressor-condenser unit needs be manufactured to take care of a wide variety of air conditioning loads. This fact coupled with the fact that no air ducts are normally required makes it possible to keep the cost of the unit down to a minimum without sacrificing in quality and in performance. In fact, it has now been demonstrated that systems of the general type disclosed herein surpass the prior art systems in all-around performance. This is especially true when personal comfort is taken into consideration. By virtue of the fact that the units are all of the self-contained type, the entire refrigeration circuit may be assembled and tested by the experienced factory workers rather than by the less skilled field representatives.

In order to simplify this disclosure, all of the controls have been shown as dry bulb thermostats, whereas, it is within the purview of this invention to substitute wet bulb thermostats, effective temperature thermostats, hygrometers, or a combination of two or more of these controls for any one of the controls shown. It is also within the purview of this invention to provide inside controls which are modified in accordance with changes in the outside air conditions. Controls of this type are now well known and need no further description.

The same general arrangement of heat exchange coils as shown herein could also be used for heating the enclosure merely by providing conventional means, not shown, for reversing the refrigerant cycle of each refrigeration system. It is also apparent that many features of my invention are equally applicable to non-residential air conditioning systems and to various types of systems using ducts for distributing the air.

While the form of embodiment of the invention as herein disclosed, constitutes a preferred form, it is to be understood that other forms might be adopted, all coming within the scope of the claims which follow.

What is claimed is as follows:

1. In combination, a first evaporator, a second evaporator, means for supplying liquid refrigerant to said evaporators including refrigerant condensing means, a water coil, means for flowing air to be conditioned in thermal exchange with said water coil and thereafter in serial thermal exchange relation with said evaporator, means for supplying water to said water coil, and means for discharging the water leaving said water coil in thermal exchange with said condensing means, and means, responsive to the temperature of the air, for by-passing one of said evaporators with a portion of the air.
2. In combination, a first evaporator, a second evaporator, means for supplying liquid refrigerant to said evaporators including a plurality of refrigerant condensing means, a water coil, means for flowing air to be conditioned for an enclosure in thermal exchange with said water coil and thereafter in serial thermal exchange relation with said evaporators, means for supplying water to said water coil, means for discharging the water leaving said water coil in thermal exchange with one of said condensing means, and means responsive to the temperature of the air in the enclosure for rendering another of said condensing means inoperative at light air conditioning loads.
3. Air conditioning apparatus comprising in combination, a first self-contained volatile refrigerant air conditioning unit, comprising an evaporator, compressor, and a condenser mounted within a cabinet, a second self-contained air conditioning unit comprising an evaporator, compressor and condenser mounted within a cabinet, means for flowing air to be conditioned in thermal exchange with the evaporator of said first unit so as to cool said air, means for discharging the air thus cooled into said second named cabinet, means for flowing at least a portion of the air entering said second named cabinet in thermal exchange with the evaporator of said second unit, and means for by-passing a varying amount of air around the evaporator of said second unit, an air outlet for said second named cabinet, a plenum chamber adjacent said outlet into which all of the air is discharged, said plenum chamber having an outlet in the bottom wall thereof through which the air is discharged downwardly into a space to be conditioned.
4. Air conditioning apparatus comprising in combination, a first volatile refrigerant air conditioning unit, comprising an evaporator, compressor, and a condenser, a second air conditioning unit comprising an evaporator, compressor and condenser, cabinet means enclosing said units, means for flowing air to be conditioned in thermal exchange with the evaporator of said first unit so as to cool said air, means for flowing at least a portion of the air leaving the first evaporator in thermal exchange with the evaporator of said second unit, means for by-passing a varying amount of air around the evaporator of said second unit, an air outlet from said cabinet means, and a plenum chamber adjacent said outlet into which all of the air is discharged, said plenum chamber having an outlet in the bottom wall thereof through which the air is dis-

charged downwardly into a space to be conditioned.

5. Air conditioning apparatus comprising in combination, a first self-contained volatile refrigerant air conditioning unit, comprising an evaporator, compressor, and a condenser mounted within a cabinet, a second self-contained air conditioning unit comprising an evaporator, compressor and condenser mounted within a cabinet, means for flowing air to be conditioned in thermal exchange with the evaporator of said first unit so as to cool said air, means for discharging the air thus cooled into said second named cabinet, means for flowing at least a portion of the air entering said second named cabinet in thermal exchange with the evaporator of said second unit, and means for by-passing a varying amount of air around the evaporator of said second unit, said cabinet having an outlet in the bottom wall thereof through which the conditioned air is discharged downwardly into a space to be conditioned.

6. Air conditioning apparatus comprising in combination, means forming an air flow passage, a first evaporator in said air flow passage, a second evaporator in said air flow passage, means for supplying liquid refrigerant to said first named evaporator, means for supplying liquid refrigerant to said second named evaporator, means for flowing air to be conditioned in thermal exchange with said first named evaporator and thereafter in thermal exchange with said second named evaporator, means for by-passing said second named evaporator with at least a portion of the air, damper means controlling said by-pass, circuit means for energizing said means for supplying liquid refrigerant to said second evaporator, switch means in said circuit means, air temperature responsive means controlling said damper and said switch means, said air temperature responsive means being so constructed and arranged that said switch means is opened when said damper means occupies a position in which substantially all of the air by-passes said second named evaporator.

7. In combination with a building having a room above the space to be conditioned, air conditioning apparatus disposed within said room comprising in combination, a first evaporator, a second evaporator, refrigerant liquefying means for supplying liquid refrigerant to said first evaporator, refrigerant liquefying means for supplying liquid refrigerant to said second evaporator, means for flowing all fresh air to be conditioned in thermal exchange with said evaporators and for discharging the air downwardly into the conditioned space, said last named means being so constructed and arranged that all of the air flows in thermal exchange with said first named evaporator and a variable amount of air flows in ther-

mal exchange with said second evaporator, and control apparatus responsive to the temperature of the air for controlling the amount of air which flows in thermal exchange with said second evaporator and for rendering the means for supplying liquid refrigerant to said second evaporator ineffective when said first evaporator has ample capacity to cool the air the desired amount.

10 8. In combination with an enclosure to be cooled; a first evaporator; a second evaporator; means for supplying liquid refrigerant to said evaporators including refrigerant condensing means; a water coil; means for flowing air, at least the greater portion of which is fresh air, in thermal exchange relation with said water coil and thereafter in serial thermal exchange relation with said evaporators; means for discharging the air leaving said evaporator downwardly into said enclosure; means for supplying water to said water coil; means for discharging the water leaving said water coil in thermal exchange with said condensing means; and means, responsive to the temperature of the air, for by-passing one 25 of said evaporators with a portion of the air.

9. In combination, a first evaporator, a second evaporator, means for supplying liquid refrigerant to said evaporators including a plurality of refrigerant condensing means, a water coil, means for flowing air to be conditioned for an enclosure in thermal exchange with said water coil and thereafter in serial thermal exchange relation with said evaporators, means for supplying water to said water coil, means for discharging the water leaving said water coil in thermal exchange with one of said condensing means, means responsive to the temperature of the air in the enclosure for rendering another of said condensing means inoperative at light air conditioning loads, and cabinet means enclosing said evaporators, said cabinet means including a plenum chamber having an outlet for discharging the air downwardly.

10. In combination, a first evaporator, a second evaporator, means for supplying liquid refrigerant to said evaporators including a plurality of refrigerant condensing means, a water coil, means for flowing air to be conditioned in thermal exchange with said water coil and thereafter in serial thermal exchange relation with said evaporators, means for supplying water to said water coil, means for discharging the water leaving said water coil in thermal exchange with one of said condensing means, and means for rendering another of said condensing means inoperative at light air conditioning loads, said last named means including means for by-passing one of said evaporators with at least a portion of the air.

ANDREW C. FREIMANN.
